UNITED STATES PATENT OFFICE

FRED M. CARROLL, OF YONKERS, NEW YORK, ASSIGNOR TO THE TABULATING MACHINE COMPANY, OF ENDICOTT, NEW YORK, A CORPORATION OF NEW JERSEY

PRINTING MECHANISM FOR TABULATING MACHINES

Application filed June 22, 1928. Serial No. 287,549.

This invention relates to printing mechanisms, in general, and more particularly to the paper feeding mechanisms for accounting machines whereby the paper may be spaced variable amounts to meet some particular requirement.

Machines of the type to which the present improvements have been applied are employed in varied lines of business, the 10 counting practices and requirements of which are similarly diversified. At the present time the accounting and printing portions of such machines are almost universal so that a standard type of machine 15 may be altered to meet the various needs. Heretofore the efficiency of such machines has been reduced inasmuch as no provision has previously been made for varying the paper feed to conform to the different requirements. It is then a broad object of the 20 present invention to provide a paper feeding attachment that is substantially universal in its functions and one that may be readily altered to meet the different requirements and needs.

More specifically it is a further object of the present invention to provide a means for driving a paper feeding mechanism and determining the extent of operation thereof.

It is a still further object of the present invention to provide an improved means whereby a long work sheet is fed prior to and after total taking operations in order that the last item may be suitably separated 35 from the total for purposes of identification and that the total may be suitably spaced from the first item of a following group of items.

In connection with spacing items and totals it is a further object to provide improved means to automatically space the paper if a total should be taken prior to the completion of the listing operations.

It is a still further object of the present 45 invention to provide means whereby several pairs of feeding rollers may be driven simultaneously or independently by the listing and total taking mechanism to provide for feeding narrow or wide record sheets and 50 by selective means to provide for printing

the items on one sheet and the totals on another.

It is a still further object of the present invention to provide means whereby totals may be successively printed without related 55 items and the paper spaced to accommodate such totals and selectively controlled by the total taking driving means or the usual listing driving means.

Other objects of the invention will be clear 60 from the following detailed description which should be read in connection with the accompanying drawings, in which:

Fig. 1 is a view in side elevation of a conventional form of tabulator with the improved attachment associated therewith;

Fig. 2 is a front view in elevation of the machine shown in Fig. 1;

Fig. 3 is a cross sectional view of the paper feeding device associated with the total 70 printing mechanism taken on the line 3—3 of Fig. 2;

Fig. 4 is a cross sectional view of the paper feeding device associated with the item printing mechanism;

Fig. 5 is a view taken on the line 5—5 of Fig. 4;

Fig. 6 is a view taken on the line 6—6 of Fig. 4;

Fig. 7 is a top plan view taken on the line 80 7—7 of Fig. 3;

Fig. 8 is a diagrammatic representation of the electrical control circuits;

Fig. 9 is a fragmentary sectional view showing in detail the construction of the 85 clutches used for selecting various feeding rollers for operation;

Fig. 10 is a cross sectional view taken on the line 10—10 of Fig. 9;

Fig. 11 is a view taken on the line 11—11 90 of Fig. 9 and shows the one-way drive between the driven rollers and the driving mechanism;

Figs. 12 to 16 inclusive illustrate some of the different paper feeding operations that 95 may be performed by the present improvements.

Similar reference numbers in all of the above figures are employed to designate corresponding parts thereof.

For the purpose of illustration the present improvements are shown in connection with a Hollerith type tabulating machine, but it will be understood that with slight modifications they may be embodied in other forms of accounting machines and the present showing is to be considered as illustrative rather than restrictive.

The Hollerith type tabulator is well known in the art and exemplified in many prior patents and requires but little further description than will be given incidentally herein. As is well known, as the perforated cards are passed through the machine, one or more of the counters are operated to show the figures or the totals of the figures represented by the perforations in the cards.

The printing devices whereby numerals corresponding to the perforations in particular card columns or the amount standing on any particular counter wheel are printed, comprise a plurality of groups of type bars 20 (Figs. 1 and 2) any one of which may be impelled by suitable hammers (not shown) against a platen 21 to perform the printing functions. Inasmuch as the printing devices and the controlling devices therefor are not involved in the present application, they are not shown in detail herein. For further details of construction reference may be had to the patent to C. D. Lake, No. 1,379,268, dated May 24, 1921.

The paper strip 19 upon which is printed numerals by means of the type 20 and an inking ribbon 22 (Fig. 1) interposed between the type and the paper strip is drawn from a storage roller (not shown). The paper strip thence passes around a tension roller 23 carried by a spring-urged arm 24, then around fixed rollers 25 and 26 to the platen roller 21.

The printing mechanism is shown as equipped with a pair of paper strips 19 (see Fig. 2) and in the present case each strip after it passes around the platen 21 is led between cooperating feeding rollers of which there are two pairs designated A, B (Fig. 1) and C, D (Fig. 3) the right hand paper strip passing between the pair of rollers A, B while the left hand strip passes between the pair of rollers C, D. As each strip passes away from the related cooperating feeding rollers it is fed over a stationary guide plate 27 to permit the printed end of the paper strip to be either rolled upon a storage roller in the usual manner or be deposited in a suitable receptacle. It is obvious, of course, that a wide paper strip may be provided in lieu of two strips in which case the single paper strip will cooperate with both pairs of feeding rollers. As is best shown in Fig. 2, the feeding rollers A and C are in longitudinal alinement and are rotatably mounted upon a shaft 28, a similar construction being provided for

the feeding rollers B and D, this pair of rollers being mounted upon the supporting shaft 29. The adjacent ends of feeding rollers A and C are mounted upon the shaft 28 by means of roller bearings 30 (Fig. 2), a similar construction also being provided for rollers B and D. Each feeding roller is rotatably mounted at its other end on the supporting shaft by an annular disk 31 (Fig. 9) provided with gear teeth 32. It will be noted that the gear teeth of the parallel pairs of feeding rollers intermesh so that one may be driven by the other. Shaft 29 which supports the longitudinally alined feeding rollers B and D is fixed at its ends in the stationary frame portions of the machine but shaft 28 which carries the longitudinally alined feeding rollers A and C is carried by a pair of plates 33 and 34 (Figs. 1 and 4) loosely mounted upon a rod 35 the lower portions of each of the plates 33 and 34 having extensions to which are connected springs 36 in order to urge the pairs of feeding rollers A, B and C, D into cooperative relationship. In order to disengage the feeding rollers for the purpose of threading the paper therebetween, a rod 37 (Fig. 4) is provided and has a flattened portion 38 bearing against the extensions of the plates 33 and 34 so that as the rod 37 is rocked by means of a finger piece 39, the feeding rollers carried by shaft 28 will be disengaged from the cooperating feeding rollers.

A system of clutches is provided for the various feeding rollers whereby segments which are operable during different machine operations may drive either pair of feeding rollers. The particular manner in which this is obtained will now be described in detail.

Clutch E (Fig. 9) which controls the establishment of the driving connection between shaft 28 and the pair of feeding rollers C, D may be taken as a representative of the particular mechanical expedient adopted for shifting the driving connections to the various feeding rollers. By means of a splined connection 40 (Figs. 9 and 10) to shaft 28 a flanged collar 41 may be rotatably driven by shaft 28 as it is shifted longitudinally on a sleeve 42 encircling shaft 28. When a sufficient shifting movement has been given to collar 41 a pin 43 carried thereby will engage one of a plurality of notches 44 formed in the face of disk 31. This shifting movement is placed under control of a lever 45 pivoted at 46 and having a pin 47 engaging an annular groove 48 in the collar 41. This clutch, which is designated generally as clutch E, establishes a clutch connection between shaft 28 and feeding roller C which latter drives feeding roller D through the intermeshing gears 32. This operative connection is established by moving lever 45 to the right but when the

latter is shifted to the left a similar clutch F establishes a driving connection from shaft 29 to feeding rollers C, D, roller D, in this instance driving roller C.

5 At the right ends of feeding rollers A, B, referring particularly to Fig. 2, a clutch mechanism similar to that disclosed in Figs. 9 and 10 is provided. The clutch G establishes a connection between shaft 28 and the 10 feeding rollers A, B when a control lever 49 is moved to the left, but when lever 49 is shifted to the right a clutch H is adapted to connect shaft 29 to the pairs of feeding rollers A, B. Thus in general, either shaft 28 or 15 29 may drive either or both pairs of feeding rollers.

Shaft 29 is adapted to be driven by a gear segment 50 (Figs. 3 and 9) while shaft 28 is driven by a gear segment 51 (Figs. 4 and 9).

20 Loosely mounted on shaft 29 is a gear 52 (Figs. 3 and 9) meshing with segment 50, the gear having a hub 53 to which is attached a disk 54 carrying a pawl 55 (Fig. 11) engaging the teeth of a ratchet wheel 56. The 25 hub of the ratchet wheel 56 is reduced to receive an alining wheel 57 (Figs. 3 and 9) and a gear wheel 58, a pin 59 being adapted to secure these three elements for a unitary movement. For the present purposes it may be 30 assumed that gear wheel 58 is rigidly secured in some manner to a gear wheel 62 pinned to shaft 29 by a pin 63. Shaft 29 has attached at its end a knurled operating knob 64 to permit manual adjustment of 35 shaft 29 so that as the shaft 29 and ratchet wheel 56 are turned in the direction of the arrow shown in Fig. 11, an idle ratcheting movement will be effected between ratchet wheel 56 and pawl 55 but the clutched rollers will be turned. As the shaft 29 is 40 turned it is held in alined position by an alining pawl 65 (Fig. 3) engaging the interdental spaces of the alining wheel 57.

The driving connection between shaft 28 45 and gear 51 differs only in that the gear segment 51 drives a pinion 66 (Fig. 4) which imparts movement to a gear 69 on shaft 28 through a train of idler gears 67 and 68. It will be recalled that shaft 28 is spring- 50 urged towards shaft 29 and the purpose of the gear train just described is to thrust shaft 28 towards shaft 29 to force the feeding rollers into cooperation, thus assisting spring 36. Gear 69 is similar to gear 52 on 55 shaft 29 and has a similar connection to its shaft 28.

It will be obvious that the extent of rotation of the cooperating feeding rollers when driven by segment 51 is directly proportional to the extent of movement imparted to the segment and in the present instance, a manual control is provided to vary the extent of movement to give the proper line spacing movement when it is necessary to conform to predetermined re-

quirements. Segment 51 (Fig. 4) is attached to a segment-shaped frame 70 by suitable fastening means 71. Segment frame 70 is loosely mounted upon a stud shaft 72 and adjacent to the frame is an arm 73 carrying a pawl 74 adapted to engage the ratchet teeth 75 formed on the inner concentric edge of rack 51 to thereby drive frame 70 and rack 51. Arm 73 is given an invariable movement during machine operations and in order to vary the movement given to segment rack 51 a shield 76 is interposed between pawl 74 and ratchet teeth 75 to vary the number of effective ratchet teeth. Shield 76 is attached to a plate 77 (Fig. 7) loose on stud shaft 72 and is held in a desired position by a holding pawl 78 (Fig. 4) carried by plate 77 and engaging the interdental spaces of a fixed plate 79. A finger piece 80 movable over a scale 81 (Fig. 6) 80 indicates the degree of line spacing that may be effected by subsequent machine operations. Operating arm 73 has suitable connections to the driving parts of the machine described as follows: Power for driving the 85 various mechanisms is, in the present case, obtained by an auxiliary motor the power shaft of which has a belt connection 82 (Fig. 5) to a drive shaft 83. A pinion 84 (Figs. 3 and 5) on shaft 83 drives a gear 85, the latter being connected to a gear 86 by a sleeve 87. Gear 86 drives a gear 88 to which is attached ratchet wheels 89 and 90. Thus, through the train of gears, just described, ratchet wheels 89 and 90 are constantly rotated. Loosely mounted on a shaft 91 which carries gear 88 and ratchet wheels 89 and 90 is a cam 92 (Fig. 4) engaging a roller 93 carried by a bell crank arm 94 having a link connection 95 to an extension of the arm 90. The profile of cam 92 is so shaped as to reciprocate arm 73 during each rotation of said cam. A pawl 96 carried by cam 92 100 is adapted to engage the interdental spaces of the ratchet wheel 89 to thereby drive cam 105 92.

The mechanism for effecting the control of one of the line spacing mechanisms is under control of the ratchet wheel 89 and a magnet 97. Pawl 96 is normally held in an ineffective position by the engagement of an extension 98 with a lug 99 of a plate forming part of the pivoted armature structure 100. The attraction of the armature structure by energization of magnet 97 after each item printing operation will disengage the lug 99 from the extension 98 so that as pawl 96 engages a tooth of the ratchet wheel 89 the latter will drive cam 92 to effect a line spacing operation. Prior to the time that cam 92 completes a revolution, magnet 97 will be deenergized permitting the lug 99 to again be in the path of the extension 98 disengaging pawl 96 from ratchet wheel 89 thus stopping movement of cam 92. To prevent 110 115 120 125 130

rebound of the cam 92 in a clockwise direction caused by the sudden stopping thereof, a pin 101 carried by the cam cooperates with a downward extension of a gravity operated pawl 102 substantially at the termination of the rotation of the parts. Pawl 102 is pivoted on the pivot pin of the armature structure and has a pair of stop abutments 103 which are spaced apart a greater distance than the diameter of the cooperating rod 104 which permits pin 101 to pass idly by the extension of pawl 102 to assume the rebound-preventing position shown.

Shock to the parts operated is minimized by a spring-retarded plunger 105 (Fig. 4) to which is pivoted a slidably mounted member 106, the latter cooperating with a pin 107 carried by the frame 70. Frame 70 is restored to normal by a spring 108 and as it approaches this position the pin 107 engages the member 106 compressing a previously extended coil spring 110.

Current for operating the motor is supplied by line wires 111 and 112 (Fig. 8). The circuit for magnet 97 extends from the right side of the line 112 through the magnet 97, to contacts 113 which are in series with cam controlled contacts 114, thence to the left side of the line 111. Contacts 113 are controlled by a lever 115 which has two positions, the "List" which completes the circuit connection to magnet 97 from contacts 114 and the "Non-list" which breaks said circuit connection. Contacts 114 are timed to close after item printing operations.

The above makes it clear that if a strip of paper is inserted between feeding rollers C, D (Fig. 2) adjustment of lever 45 to the right will permit shaft 28 to drive said rollers whereby items may be listed on the strip with predetermined spacings (see Fig. 12). However, the adjustment of lever 49 to the left only will permit shaft 28 to drive rollers A, B permitting items of predetermined spacing to be effected on the strip between these rollers. If a single sheet cooperates with both pairs of rollers adjustment of levers 45 and 49 toward each other will provide for the driving of both pairs of rollers by shaft 28.

When printing items in this manner (see Fig. 13) it is frequently desirable to limit the number of items that may be placed on a sheet in order to provide a suitable spacing between the groups of items printed on a long work sheet or else insure that the number of items printed will conform to the number that may be accommodated.

A cross bar 116 (Figs. 3 and 7) is adapted to connect the arm 73 and a similar arm 117, the latter carrying a pawl 118 (Fig. 3) engaging the rack teeth 119 of the gear segment 50. Gear segment 50 is carried by a segment frame 120 also pivotally mounted on the stud shaft 72. It will

be noted that the driving mechanism for segment 50 just described is substantially a duplicate of that shown in Fig. 4; it being further noted that a shield 121 carried by a plate 122 may be adjusted by a finger piece 123 and held in adjusted position by a pawl 124 to vary the effective number of rack teeth 119. When this part of the apparatus is utilized for the purpose of limiting the number of item printings the shield is preferably adjusted so that pawl 118 effects a single ratchet tooth movement of segment 50 during each paper feeding operation. The segment 50 is held in its successively advanced positions by a spring-urged retaining pawl 125 also cooperating with the ratchet teeth 119. As the gear segment 50 is moved downwardly an adjustable block 126 slidably in a concentric groove in frame 120 and rigidly held by a screw 143 advances towards a finger 127 of a contact control member 128 and opens contacts 129 when the block 126 actuates the finger 127.

Since contacts 129 are preferably in the motor circuit of the tabulating machine the driving motor will thereupon stop and card and paper feeding operations will cease. Block 126 is preliminarily adjusted when segment 50 is at normal so that its position adjacent a scale 109 (Fig. 6) will indicate the number of items that may be printed.

Restoration of the gear segment to its normal starting position may be provided for by manually disengaging pawl 125 (Fig. 3) so that a spring 130 may return the advanced parts, the shock being absorbed by a cushioning device 131 similar to the one previously described.

It has been assumed that levers 45 and 49 (Fig. 2) have been moved toward each other so that the feeding rollers are driven by shaft 28 to feed a wide paper strip. However, if levers 45 and 49 are moved away from each other the feeding rollers will be driven by shaft 29 instead, the spacing of successive items being determined by the setting of the pawl 124. It is preferable, however, to drive the feeding rollers by shaft 28 when a spacing is desired that does not conform to the successive advancement of segment 50 corresponding to a ratchet tooth space, otherwise scale 109 may not correctly indicate the number of items that may be printed.

The machine may be adjusted so that the item printing limiting mechanism is inoperative while segment 50 is driving the feeding rollers. To this end latch 125 may be retained in disengaged position with respect to ratchet teeth 119 by a pawl 132 (Fig. 3). Segment 50 will therefore, be returned to normal after being actuated during each paper feeding operation.

As previously stated the items listed are

- preferably represented by punched cards, and in rendering a statement of items of a person's account as represented by punched cards it is desirable to obtain a total of 5 such items and print the same below the last item (see Fig. 14). The present machine also provides for this to give a different spacing before and after total printing operations in the following manner.
- 10 The particular mechanism for controlling machine operations to print a total of a group of items either automatically or manually is shown and described in the Lake Patent No. 1,379,268 and in the present construction numeral 133 (Fig. 3) indicates a magnet which controls the spacing of the paper upon instituting total printing operations. As shown in Fig. 8 this magnet is in series connection with cam controlled contacts 134 which close so as to energize magnet 133 before a total printing operation is instituted and performed in the manner explained in the Lake patent. Prior to total printing operation the paper will, however, 20 be spaced by the usual item spacing mechanism to additionally separate the item from the total. In this case shaft 29 is utilized to drive the feeding rollers and the extent the paper is fed between successive item 25 printing operations in proportional to the setting of finger piece 123 and where items are merely listed on a long work sheet (Fig. 14), a space is provided before and after each total printing operation. When it is 30 desired to have a paper feed before and after a total taking operation the feeding rollers are driven by shaft 29, the operating connection being from gear segment 50. Pawl 125 is adjusted to be held out of engagement with the ratchet teeth 119 by pawl 35 132 so that segment 50 may be returned after each actuation by pawl 118 and the block 126 is preferably adjusted to the dotted line position shown in Fig. 3.
- 40 Upon the initiation of a total taking operation cam contacts 134 close immediately 45 to energize magnet 133. The cam portion 135a (Fig. 3) will thereupon rock arms 139 and 141 and since block 126 is in direct 50 contact with a finger 142 of arm 141 segment 50 will be depressed to feed the paper strip before a total printing operation. As the dwell 135b of cam 135 is in operative 55 relationship with the roller of arm 139, paper feeding operations will be suspended and a total printing operation will occur during this time. Subsequently the cam portion 135c will rock arms 139 and 141 further to again feed the paper strip after 60 the total printing operations.
- When printing upon a long work sheet this will provide for a head space between the last printed total and the next group of items to accommodate preprinted matter.
- 65 By adjusting block 126 to provide for a lost motion between the block and finger 142 a variable paper feed between the last item printed and the total may be provided for. When printing upon work sheets of cut lengths the paper feed subsequent to total printing operations insures that the paper will be entirely fed out from the feeding rollers to permit the insertion of the next work sheet.
- The machine, moreover, may be adjusted 75 so that a predetermined number of items may be printed and a total printed at the last item printing position on the sheet if a total should be taken before a predetermined number of item printings have 80 been effected. In this instance pawl 125 is released to hold segment 50 in its successively advanced positions, block 126 gradually approaching finger piece 127. If a total taking operation should be instituted prior to the time that block 126 has completed the length of its travel which is commensurate with the number of items to be printed, magnet 133 will then be energized resulting in a downward movement of arm 141 and as finger 142 contacts with block 126 it will move segment 50 the remainder of the distance. This will result in feeding the paper strip the distance it would have been if a predetermined number of item 95 printings was effected, (see example shown in Fig. 15).
- In this instance as arm 141 is depressed a camming finger 144 thereof will coat with a lug 145 of pawl 125 disengaging it from ratchet teeth 119 to permit the advanced parts to be returned to normal simultaneously with the return of arm 141. Since contacts 129 are opened operation of the tabulator will be stopped.
- In total taking operations it will be observed from the circuit diagram (Fig. 8) that when the lever 115 is in the position shown the circuit for magnet 133 is established from the left side of the line 111 to the right side of the line 112 through cam controlled contacts 134.
- The listing control lever 115 is also shown in Fig. 3 and is adjusted by an arm 150 connected thereto by a link 149, said arm having two possible positions. When the arm 150 is moved to the "non-list" position contacts 113 will be opened and contacts 146 closed. At the same time a pin 147 carried by an extension of the pawl 125 cooperating with a closed slot in the link 149 will hold pawl 125 in an inoperative position.
- In certain accounting operations it may be desirable to list the successive totals only (see Fig. 16). The present invention also provides for this as follows and such operations may be controlled by either magnet 97 or 133. When lever 115 (Fig. 8) is adjusted to the non-list position the circuit through magnet 97 will be closed by closed

contacts 146 and cam controlled contacts 134. Levers 45 and 49 (Fig. 2) are adjusted towards each other when it is desired to space a wide paper sheet by driving shaft 28.

5 The extent of spacing of the totals, in this instance, will be controlled by the setting of finger piece 80 (Fig. 4).

When it is desired to space the paper strip for totals by driving shaft 29, levers 10 45 and 49 are adjusted towards each other. Spacing of the record strip will occur before and after total printing operations, as previously described. Block 126 is preferably removed from frame 120 so as not to 15 stop the machine after the first total printing operations.

Attention is directed to the fact that when the control lever 115 is in the position shown in Fig. 8 the attachment may be conditioned so as to print the items in the usual manner on one record sheet and the totals on the other as illustrated in Fig. 2. In this instance lever 45 (Fig. 2) is adjusted to the right so as to establish a connection between 25 shaft 28 and the pairs of feeding rollers C, D. Segment 51 will therefore drive the feeding rollers C, D to space the items (see Fig. 2). The lever 49, however, is adjusted to the right so as to establish a connection 30 between shaft 29 and feeding rollers A, B. Total segment 51 (Fig. 4) will, therefore, drive shaft 29 and rollers A, B whenever a total is taken.

It has been assumed, referring particularly to Fig. 9, that a rigid connection is established between gear 58 and a gear 62. A different connection is preferable in order to be able to turn the feeding rollers independently slightly to conform to some predetermined spacings, such as those governed by printed lines. Without the present connection or equivalent construction a spacing less than that controlled by the interdental spaces of alining wheel 57 (Fig. 3) 45 could not be provided for. Gear 58 is adapted to mesh with a pinion 60 pivotally mounted on an annular ring 61 which is loosely mounted on the hub of the gear 62. Pinion 60 is of sufficient width to 50 mesh with gear 62. As gear 58 rotates, pinion 60 will be driven in an opposite direction and as it rolls over gear 58 it will drive gear 62. Gear 58 is preferably formed with the smaller number of teeth than gear 62, and in the present embodiment gear 58 has twenty-eight teeth while gear 62 has thirty teeth. It will be understood, therefore, that if a feeding roller is clutched to 55 shaft 29 and the shaft turned slightly by knob 64, gear 62 will rotate pinion 60 slightly but due to the relative dimensions of the teeth of pinions 62 and 58, the pinion 60 60 may rotate slightly without rotating gear 58. Thus shaft 29 may be given an inde-

pendent movement to bring the paper sheet to the proper printing position.

While there have been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention, therefore, to be limited only as indicated by the scope of the following claims:

What is claimed is—

1. In a machine of the class described the combination with a printing mechanism adapted to list data upon record sheets, of a plurality of pairs of feeding rollers, a driving rack operable automatically as an incident to listing operations, selective means whereby either pair or a plurality of pairs of feeding rollers may be driven by the driving rack, means for retaining the rack in successively operated positions, and a control device movable with the rack for predetermined the number of sheet feeding operations.

2. In a machine of the class described the combination with a printing mechanism adapted to list data upon record sheets interposed between a single or a plurality of pairs of feeding rollers, of driving means comprising a rack member, selective means whereby a single or a plurality of pairs of feeding rollers may be driven by said rack member, said rack member being provided with means for determining the number of sheet feeding operations.

3. In a machine of the class described the combination with a printing mechanism adapted to print items or totals upon record sheets, of separate pairs of feeding rollers each being adapted to feed the related record sheet, a driving means automatically driven when the printing mechanism is effective to print items, a separate driving means automatically driven when the printing mechanism is effective to print totals, and selective means whereby either driving means may drive any desired pair of feeding rollers.

4. In a machine of the class described the combination with a printing mechanism adapted to print items or totals upon separate record sheets, of line spacing means automatically operable upon either item or total printing operations to space successive items and totals, and adjustable means for controlling the line spacing means to automatically vary the spacing between a printed item and total.

5. A machine of the class described including in combination, a printing mechanism adapted to effect printing operations upon a record sheet, and selective means

whereby said record sheet may be spaced automatically as an incident to successive item printing operations or successive but different total printing operations and without intermediate item imprints.

6. A machine of the class described including in combination, a printing mechanism adapted to effect printing operations upon a record sheet, selective means including a single driving member whereby said record sheet may be spaced automatically as an incident to successive item or successive but different total printing operations and means controlled by the driving member for predetermining the number of successive items or successive totals that may be spaced on a sheet.

7. A machine of the class described including in combination, a printing mechanism for printing items and totals upon a record sheet, means for feeding the record sheet to space successively printed items, a cam, and record sheet feeding means operated by and during a single revolution of said cam whereby said record sheet is spaced prior and subsequent to total printing operations.

8. A machine of the class described including in combination, a printing mechanism for printing a total of a series of items on a record sheet, a cam, and means operated by and during a single revolution of said cam for feeding said record sheet prior and subsequent to total printing operations.

9. A machine of the class described including in combination, a printing mechanism adapted to list items and totals on a record sheet, a pair of feeding rollers cooperating with said record sheet, intermittently actuated means for driving said feeding rollers to space the record sheet as an incident to item printing operations, and a cam automatically operable as an incident to total printing operations and by a single revolution of the cam cause an actuation of said driving means to feed the record sheet prior and subsequent to total printing operations.

10. A machine of the class described including in combination, a printing mechanism adapted to list items on a record sheet, a pair of feeding rollers cooperating with said sheet, an intermittently actuated member adapted to drive said feeding rollers to space the successively printed items and an adjustable stop device carried by said member for predetermining the number of items to be printed.

11. A machine of the class described comprising in combination, a printing mechanism adapted to print items on a record sheet, a pair of feeding rollers cooperating with said record sheet, a rack member adapted to drive said rollers, means for holding said rack member in successively advanced positions, and an adjustable device

carried by said rack member for predetermining the number of items to be listed.

12. In a machine of the class described, the combination with a printing mechanism adapted to print upon record sheets, of a plurality of pairs of feeding rollers, a common driving means therefor automatically operable as a result of a printing operation for driving said rollers to feed said record sheet in an alternating sequence with respect to printing operations, and selective means whereby either pair of feeding rollers may be driven by the common driving means.

13. In a machine of the class described the combination of a printing mechanism for printing totals on a record sheet, and a cam having cam portions effective for spacing the record sheet prior and subsequent to total printing operations, said cam having a dwell intermediate said cam portions and ineffective during the rotation of the cam to space the work sheet while total printing operations are being effected.

14. In a machine of the class described, the combination with a printing mechanism for printing items and totals on a record strip, of record strip spacing mechanism automatically operable when the printing mechanism is effecting item printing operations on one strip, supplemental record strip spacing mechanism automatically operable when the printing mechanism is effecting total printing operations on another strip, and selective means whereby the first mentioned spacing mechanism is also automatically rendered operable when the printing mechanism is printing totals on both strips.

In testimony whereof I hereto affix my signature.

FRED M. CARROLL.
